UNITED STATES PATENT OFFICE.

ROBERT E. MCGAHEY, OF ALEXANDRIA, VIRGINIA.

LOCK FOR DUMP CARS.

Application filed July 28, 1926. Serial No. 125,456.

This invention relates to locks for dump cars and the like and has for an object to provide a lock embodying new and improved features of convenience in operation 5 and security of action.

A further object of the invention is to provide a lock of improved type embodying new and improved features to facilitate the closing of the door.
10 A further object of the invention is to provide in a lock new and improved features whereby the door may be maintained in a partially open position for the purpose of discharging a small volume of the material 15 from the car as the car is being moved along.

With these and other objects in view, the invention comprises certain novel parts, elements, units, combinations, constructions, 20 mechanical movements and functions as disclosed in the drawings together with mechanical and functional equivalents thereof as will be hereinafter more fully described and claimed.

25 In the drawings:

Figure 1 is a perspective view of the lock applied to a conventional type of dump car showing the dump car closed and locked with a hammer in position to unlock the door.

30 Figure 2 is a perspective view of the lock showing the means of closing the door, also the means of maintaining the door in partially open position.

35 Figure 3 is a view of the lock in side elevation with the door connected therewith locked.

40 Figure 4 is a view of the lock in edge elevation as indicated by line 4-4 of Figure 3 which sections the hasp.

Figure 5 is a longitudinal sectional view taken on line 5-5 of Figure 3.

45 Figure 6 is a view in elevation of the lock member.

Figure 7 is a view in elevation of the key member.

Like characters of reference indicate corresponding parts throughout the several views.

50 It is well understood that dump cars are now in use embodying inclined hopper or chute bottoms indicated at 10 with hinged doors as indicated at 11, the opening of which discharges the material from the hopper bottom 10.

It has proved a great problem in rolling stock engineering to provide adequate locking facilities for the door to maintain the door safely and securely in locked position and at the same time to make the unlocking 60 of the door convenient and easy.

The present invention comprises a body 12 which attaches to the end of the hopper bottom sections which in effect are usually the sides of the car, such attaching means being by any usual and ordinary mechanical devices, such as the bolts 13, which are inserted through openings 14 provided for the purpose.

The body 12 is provided with an opening 70 or passage 15 through which the hasp 16 attached to the door passes. This hasp 16 is preferably attached to a structural steel or iron bar 17 which extends throughout the length of the door and it is the intent to use 75 one of these locks upon each end, it being understood that each is the equivalent of the other and only one is shown. This bar 17 extends beyond the end of the door to provide attaching the hasp 16 thereto by 80 means of a block 18 to which the hasp is hinged or pivoted as at 19.

Mounted to slide in the body 12 and to transect the opening 15 is a lock member 20 and the hasp is provided with one or more 85 slots 21 properly proportioned to accommodate the key 20 when the hasp has been drawn or otherwise moved into such position as to completely close the door in the position shown at Figures 1 and 3. This lock 90 20 is provided with an overhang head 22 so that a hammer as indicated at 23, or other convenient utensil, may be used to drive the lock upwardly from the position shown at Figures 1, 3, 4 and 5 which is the 95 locked position to the unlocked position, as shown at Figure 2. In locking the door, the hammer may also be employed upon the top of the overhang head 22 for driving the lock home.

For this purpose, the lock is 100 preferably provided with a chamfered corner 23', as shown more particularly at Figure 6, for engaging the edge of the slot 21 and drawing the hasp and the door connected therewith more tightly to closed position. The lock is also provided with a slot 105 24 through which a pin 25 is inserted to limit the movement of the lock and also prevent its complete displacement from the body 12.

To add to the security of the lock, a key 26 is employed having a tongue 27 properly positioned and proportioned to enter the groove 28 of the lock 20 when the lock 20 is in seated position as indicated at the figures showing the several members locked. This key 26 is also provided with a slot 29 through which a pin 29 is inserted for the purpose of limiting the movement of the key and also preventing its displacement. It will be noted, especially from Figure 3, that in locked position the slotted end of the key extends beyond the body 12 so that a hammer or other implement may be employed to drive the key 26 in the direction indicated by the arrow at Figure 7, which will disengage the tongue 27 from the groove 28, which is a step preliminary to driving the lock 20 from its seat by the engagement of a hammer or like implement under the overhang head 22.

The hasp 16 is also provided with one or more perforations 30 through which a bar 31 may be inserted as a leverage bearing against the body 12 to draw the door 11 to closed position. The bar or its equivalent may also be employed inserted through one of said perforations to maintain the door in partially open position so that, as before mentioned, the contents will be slowly discharged as the car is moved or for any other purpose.

In operation, starting with the door locked as shown at Figure 3, the key 26 is first driven in the direction indicated by the arrow which disengages the tongue 27 from the groove 28 and frees the lock 20. The lock 20 is now raised by being struck under the overhanging head 22 until it is removed from its engagement with the slot 21 of the hasp 16. This frees the hasp entirely and it may swing outwardly with the door leaving the body entirely or by the insertion of the bar 31 in one of the perforations 30 its movement may be limited. When the material has been discharged and it is found desirable to close the door, the door is swung to position and the hasp 16 entered into the opening 15 simultaneously upon each side of the car. Under ordinary conditions, the door may be simply swung to shut position manually, whereupon the lock 20 may be forced home either by the hand or a driving implement and secured in such position by the key 26 which may be driven home by the use of a hammer.

What I claim to be new is:

1. The combination with a dump car embodying a hinged door, of a lock secured to the end adjacent the door and comprising a body having a passage therethrough, a hasp carried by the door adapted to be inserted through the passage of the body and provided with a perforation, and a lock member slidably carried by the body, prop-

erly proportioned and positioned to enter and pass through the perforation of the hasp.

2. The combination with a dump car embodying a hinged door, of a hasp pivoted to the door beyond the end of the door, a lock comprising a body secured in the path of movement of the hasp and provided with an opening properly proportioned to permit the hasp to pass therein to and through, said hasp being provided with a perforation, a lock slidable in the body normally at right angles to the hasp and proportioned to enter into and through the perforation, and a key slidable transversely relative to the lock and adapted to maintain the lock in locked position.

3. A lock for dump cars comprising a body having a passage therethrough, a hasp adapted to be connected to the door of a car and proportioned to pass through the opening of the body and provided with a perforation, a lock slidable in the body and proportioned to pass through the perforation of the hasp, an overhanging head formed upon the lock adapted to facilitate the driving of the lock in either direction, and a key properly positioned to retain the lock in locked relation to the hasp.

4. A lock for dump cars and the like comprising a body having a passage therethrough, a lock slidable relative to the body and positioned to transect the passage, said lock being provided with a slot, a pin inserted through the slot adapted to limit the movement of the lock, and a key member movable transversely relative to the lock adapted to hold the lock in locked position.

5. A lock for dump cars comprising a body having a passage therethrough, a lock slidable in the body and proportioned to transect the passage, a hasp proportioned to enter into and through the passage and provided with a preferably properly proportioned opening to receive the lock, a key member slidable relative to the lock, and tongue and groove connection between the key and the lock.

6. A lock for dump cars comprising a body having a passage therethrough, a lock slidable in the body and transecting the passage, means limiting the sliding movement of the lock, a hasp properly proportioned to pass into and through the passage and provided with an opening properly proportioned to receive the lock, a key slidable transversely relative to the lock, and a tongue formed upon the key adapted in one position to enter a complementary groove on the lock and maintain the lock in locked position.

7. A lock for dump cars and the like comprising a body having a passage therethrough, a lock slidable in the body and transecting the passage, a hasp adapted to

be attached to the door and provided with an opening properly proportioned to receive the lock, said hasp being also provided with other perforations adapted to receive a bar 5 as a lever for moving the hasp within the housing to position for interaction with the lock.

8. A lock for dump cars comprising a body having a passage therethrough, a hasp 10 adapted to be attached to the door and provided with a plurality of openings, a lock member carried by the body properly proportioned to interengage with one of said openings to maintain the door in closed position, said hasp being also provided with other openings spaced from the said lock 15 receiving opening, and a bar adapted to be

inserted through one of said last mentioned perforations to maintain the door in partially open position. 20

9. A lock for dump cars and the like comprising a body having a passage therethrough, a hasp adapted to be attached to the door and proportioned to enter into and through the passage and provided with an opening, a lock member slideable within the body and proportioned to pass through the opening, and a drive head formed upon the lock overhanging and extending beyond the lines of the body, said lock being proportioned to pass through the opening of the hasp. 25 30

In testimony whereof I affix my signature.
ROBERT E. McGAHEY.
